UNITED STATES PATENT OFFICE.

PIETER VAN GELDER, OF SOWERBY BRIDGE, COUNTY OF YORK, ENGLAND.

GRAIN-SEPARATOR.

SPECIFICATION forming part of Letters Patent No. 282,415, dated July 31, 1883.

Application filed March 2, 1883. (No model.) Patented in England July 18, A. D. 1882, No. 3,415.

To all whom it may concern:

Be it known that I, PIETER VAN GELDER, of Sowerby Bridge, in the county of York, in the Kingdom of England, have invented certain new and useful Improvements in Grain-Separators, (for which a patent was granted me in Great Britain on the 18th day of July, 1882, No. 3,415,) of which the following is a specification.

10 My invention relates to that class of machines used more particularly for removing garlic and other impurities from wheat, which consists, essentially, of a revolving cylinder, against which the grain is delivered, provided 15 in its surface with holes or pockets adapted to take up and remove from the mass certain classes of seeds or matters, leaving the remainder behind.

20 The improvement relates mainly to an improved form of the cells or pockets, to the means for presenting grain to the cylinder, and to means whereby the feeding and delivering devices may be adjusted circumferentially about the cylinder.

25 Referring to the accompanying drawings, Figure 1 represents a side elevation of my improved machine. Figs. 2 and 3 are elevations of the same, looking against the opposite end. Fig. 4 is a vertical section through one side of the cylinder. Figs. 5 and 6 are face views of 30 portions of the same, showing pockets of different forms, adapted for the removal of different matters. Fig. 7 is a vertical section through one side of the cylinder and feeding mechanism and attendant parts. Fig. 8 is a top plan view of one of the yielding guards employed to remove matters which are lodged improperly in the pocket. Fig. 9 is a top plan view of a portion of the feed-screw. Fig. 10 is a top plan view illustrating a modified construction.

Referring to Figs. 1, 2, and 3, A represents rigid beams or supports, which are to be constructed in any suitable form and of any suitable material, either as a portion of one frame, or otherwise. Upon the respective beams A are mounted two journal blocks or bearings, B, designed to give support to opposite ends of a horizontal cylinder and its attendant parts.

E represents the cylinder, arranged in a horizontal position and secured upon a central driving-shaft, D, the ends of which are extended through and receive, indirectly, support from the bearings B, the cylinder being free 55 to revolve. The cylinder, which may be built of wood, metal, or other material in any suitable manner, is provided on its outer surface with a great number of small holes or pockets, e. (Clearly represented in Figs. 4, 5, 6, and 60 7.) These cells, of a size corresponding with that of the grains or particles which they are to receive and convey away from the mass of grain, are made in vertical section, of a form shown in Figs. 4 and 7, their upper walls inclining gradually backward into the surface of the cylinder, while their lower edges are extended abruptly outward to the periphery, preferably with a slight curvature forward in the direction of rotation. In other words, the 65 lower edge of the pocket extends inward at substantially right angles to the circumference of the cylinder, while the upper edge or surface extends inward at a less angle. This construction adapts the pockets to readily receive 70 and retain seeds or other particles of proper size, and which will be carried upward therein, as the cylinder revolves in the direction indicated by the arrows, without a tendency to roll outward, or escape in a backward direction 75 therefrom. The gentle inclination at the front or upper edge of the pocket, however, admits of the seeds being readily removed 80 therefrom in a forward direction—that is to say, in the direction in which the cylinder revolves. The pockets, of the form represented 85 in Fig. 5, are adapted to receive and retain cockle or other small seeds, while those represented in Fig. 6 are adapted to receive the wheat.

90 Outside of the cylinder I employ a framework to carry the feeding and discharging mechanisms constructed in the following manner: A vertical plate or frame, C, is mounted at each end of the cylinder and provided with 95 a tubular journal arranged to encircle the central shaft, D, of the cylinder, and seated loosely in the corresponding journal box or bearing, B. The tubular journals thus arranged serve 100 to sustain the plates C and admit of their re-

volving around the shaft D, and at the same time they serve as bearings for said shaft.

Lengthwise of the cylinder I extend plates C' C', secured at their ends firmly to the rock-
5 ing end plates, C, and constituting, in connec-
tion therewith, a frame-work free to rock or
tip about the cylinder E, to a limited extent,
this frame being designed to give support to
the feed-spout and screw, the discharging-
10 brush, and the delivery-worm. Upon one of
the plates C', and extending the entire length
of the cylinder, I form or attach a feed-trough,
F, having an open side adjacent to the cylin-
15 der, in order that the grain received therein
may lie in contact with the surface of the cyl-
inder, to the end that those seeds which are
to be removed may enter the cells or pockets.

As shown in Fig. 7, the bottom of the feed-
20 trough F is inclined downward toward the sur-
face of the cylinder to facilitate the flow of
grain toward the same. At its lower side the
trough is provided with a lip, f', of felt or
25 equivalent flexible material, the edge of which
is curled upward against the surface of the
cylinder, as shown in Fig. 7, and in operation
held in contact therewith by the pressure of
30 the grain above. This construction effectually
prevents the escape of the grain between the
edge of the hopper and the surface of the cyl-
inder.

The feeding-trough F communicates at one
end with an inlet or feed-spout, F', through
which the uncleared grain is delivered into
35 the machine, and communicates at its oppo-
site end with a spout, F'', through which the
purified grain is discharged.

Lengthwise within the feed-trough F, I mount
a horizontal shaft, G, bearing at its ends in
40 the end plates, C, and provided through its
length with a series of spiral or oblique blades,
g, by means of which the mass of grain in the
trough is thoroughly agitated, so that each
45 particle may come in contact with the cylinder
and be gradually passed through the ma-
chine from the head to the tail. The con-
struction of this agitator and feeder may be
modified as regards the details, provided it is
50 adapted to operate with the effect above de-
scribed.

Above the feed-shaft G, preferably upon one
and the same shaft, extending lengthwise of
55 the machine, are a series of yielding guard-
arms, Q, the forward ends of which will rest
against or in close proximity to the surface of
the cylinder, in order that they may act upon
and remove from the cells any large particles
60 which may accidentally lodge therein and be
carried upward by projecting therefrom.

It will be understood that the guards will
65 have no effect upon the small grains seated
entirely within the pockets, and that their ac-
tion will be confined entirely to those which
project beyond the surface of the cylinder.

The guards Q may be of any suitable form
65 and construction, provided only that their op-
erative faces lie in close proximity to the cyl-

inder. It is preferred, however, to construct
them of elastic wire in a U form, as repre-
sented in Fig. 8, with their outer or rear ends,
R', coiled and secured in position, as shown 70
in Fig. 7. It will be understood that there
will be a sufficient number of these guards
placed side by side to extend the entire length
of the cylinder, each free to rise and yield in-
dependently of the others. 75

On the opposite side of the cylinder from
the feed-trough, and extending the entire length
thereof, I mount a revolving brush, I, the
journals of which are seated in the end frames,
C. By means hereinafter described this brush 80
is caused to revolve and its active surface
moved in the same direction as the adjacent
surface of the cylinder, but at a higher speed,
whereby it is caused to act upon and remove
from the cells the seeds contained therein. 85
The seeds thus removed descend by gravity
past the rear side of the cylinder into a trough
or receiver, J, located between the lower edges
of the plates C' C', and sustained thereby and
by the end plates, C. 90

The trough J contains a worm or screw, K,
of any ordinary or suitable form, whereby the
delivery of the seeds is effected at the end of
the machine.

The operation is as follows: The grain to be 95
purified is delivered through the spout F' into
the trough F, and is distributed lengthwise
therein by means of the revolving blades g.
The cylinder being set in motion, its surface
moves upward past the open side of the feed
trough against the side of the mass of grain
resting thereon, the grain being agitated so
that each and every grain is brought with cer-
tainty against the surface of the cylinder, the
grain being at the same time gradually moved
lengthwise of the cylinder. Those seeds or
40 impurities which the pockets are adapted to
receive enter said pockets and are carried up-
ward therein, over the top of the cylinder, and
descending on the opposite side, fall from the
pockets, or, in the event of their failing so to
do, are removed by the action of the brush I,
and descend to the bottom spout, J, from which
they are delivered by the screw. Those large
seeds, if any, which may by chance be re-
tained in the pockets will encounter the guards
105 Q, whereby they will be displaced from the
pockets and caused to fall back into the mass
below. 110

Owing to the wide difference between differ-
ent masses of grain as regards the character
and amount of impurities contained therein,
and other circumstances, it is desirable that
the position of the delivery-brush I and the
height and inclination of the feed-spout with
120 respect to the cylinder shall be susceptible of
adjustment to suit the requirements of each
case. It is for this purpose, mainly, that the
frame supporting said parts is arranged, as be-
fore mentioned, to rock or tip upon the cen-
tral journals. 125

It will be observed that the feed-screw, the

feed-trough, the brush, and the delivery-spout are all sustained by the end plates, C, and that the rocking motion of these plates will change the position of said parts with respect 5 to the cylinder without changing their positions in relation to each other.

Any suitable means may be employed for rocking the end plates or frames, C, and for securing them in different positions—a simple 10 means consisting, as represented in Figs. 2 and 3, of links M, pivoted at *m* to the supporting-beams A, and provided on their upper ends with slots, through which clamping-bolts *n* pass into the frames C.

15 It is obvious that the cells or pockets of the cylinder may be adapted to receive the wheat or other grain and remove the same, leaving grain of smaller size, or that they may be adapted to receive the small impurities or seeds, 20 leaving the wheat.

If it be desired to have the machine remove two or more kinds of seed, the surface of the cylinder may be divided transversely into two or more lengths or sections, and the surface of 25 each section provided with cells adapted to receive a particular kind of seed only. The result of this arrangement, which is represented in Fig. 10, will be that the seed in the course of its passage lengthwise of the cylinder, will 30 first have one class of seeds removed by one series of pockets, and then be brought opposite a second series of pockets, by which another class of seeds will be removed, and so on repeatedly.

35 It is preferred to construct the feed-worm or screw of a series of short hubs or sleeves arranged end to end upon a shaft, and each bearing two or more blades, as shown in Fig. 9, this construction permitting the removal of a 40 broken section and its convenient replacement by another.

The present invention is restricted to those matters and things which are hereinafter claimed, and as to all matters which may be 45 described or shown, but which are not claimed, the right is reserved to make the same the subject of a separate application.

Motion will be ordinarily communicated to the machine through the shaft D of the cylinder, 50 by means of a pulley or equivalent device connected therewith. For the purpose of imparting motion thence to the other moving parts I adopt the following arrangement: The shaft of the brush I is provided at one end 55 with a chain-wheel, L. The shaft of the delivery-screw is provided with a chain-wheel, L'. The feed-shaft G is provided with a pulley, L'', and an adjustable spindle or arbor on one of the end plates, C, is provided with two 60 united chain-wheels, L''', and the main shaft D is provided with a large chain-wheel, L'''', as clearly represented in Figs. 1 and 3. A chain, R, (shown by dotted lines in Fig. 3,) connects the pulley L of the brush with one 65 of the pulleys, L''', and a second chain, S, (shown in the same figure,) passes around the

second pulley, L''', thence beneath and against the pulley L'''' on the main shaft, around the pulley L'' on the feed-shaft, and thence beneath the pulley L' on the delivery-screw to 70 the starting-point.

It will be seen that by this arrangement motion is communicated from the main shaft D, through the pulley L'''' and chain S, to the feed-screw, the delivery-screw, and the pulley L''', and that by means of the chain R motion is communicated from the pulleys L''' to 75 the brush.

As shown in Fig. 3, the shaft-arbor Z, which sustains the double pulley L''', is mounted in a 80 slot in the arm C, and secured by a nut on its inner end, as represented in Fig. 1, in order that it may be adjusted laterally. This adjustment of the double pulley is advantageous, in that it permits the chains to be readily applied and placed under proper tension. By 85 removing the respective pulleys and replacing them by others of different sizes the relative speeds of the different members may be varied as required.

Having thus described my invention, what I claim is—

1. In a grain-separator, the combination of the cylinder provided with cells or pockets in its surface, a feed-trough extending lengthwise of said cylinder, with the open side adjacent thereto, and a feeding device, substantially as described, to agitate the mass of grain and effect its movement through the trough lengthwise of the cylinder.

2. In a grain-separator, the combination of the revolving cylinder provided with cells or pockets in its surface, the feed-trough having an open side adjacent to said surface, and a guard located adjacent to the surface of the cylinder and above the feed-trough, whereby it is adapted to act upon those seeds which may project from the pockets and effect their return to the feed-trough.

3. In combination with the cylinder having the external cells or pockets therein, the feed-trough having the open side adjacent to said cylinder, and the yielding-guard Q, having its free end located adjacent to the cylinder and above the feed-trough.

4. In a grain-separator, a cylinder provided with cells in its surface, combined with a feed-trough having an open side adjacent to the surface of the cylinder, and a flexible lip or packing applied to the lower edge of the trough and acting against the surface of the cylinder, substantially as described, whereby the escape of the grain between the cylinder and trough is prevented.

5. The combination, with the cylinder having a cellular surface, of the feed-trough and the flexible lip or packing f', secured to the trough, and having its opposite edge curled upward against the surface of the cylinder, as shown.

6. In a grain-separator, in combination with mechanism, substantially as described, for de-

livering grain to the surface of said cylinder and for rotating the same in the direction indicated, a cylinder having in its surface cells or pockets e , the rear edges of which enter abruptly from the periphery, while the forward edges have a gradual inclination inward, as shown, whereby the escape of the seed from the cells in a forward direction is permitted.

7. In a grain-separator, in combination with mechanism, substantially as described, for delivering grain to the surface of said cylinder and for rotating the same in the direction indicated, the cylinder having in its surface cells or pockets e , the rear edges of which have an inward and backward curvature, substantially as described and shown, whereby the escape of the grain therefrom is permitted.

8. In a grain-separator, in combination with mechanism, substantially as described, for delivering grain to the surface of said cylinder and for rotating the same in the direction indicated, a cylinder having in its surface cells e , the rear walls or edges of which are carried slightly inward from the bottom to the surface in a forward direction, while their forward edges have a gentle ascent from the bottom to the surface, whereby the escape of the seed from the rear edge of the cells is prevented, but its escape from the forward edge facilitated.

30 9. In a grain-separator, a cylinder provided at different points in its length with cells or pockets of different size, combined with means, substantially as described, for effecting the movement of the grain lengthwise over the surface of the cylinder, in contact therewith,

whereby the grain is subjected to the pockets of different size, successively.

10. In a grain-separator, the combination of a cylinder having a cellular surface with the feed-trough and a delivery-brush mounted in supports arranged to revolve about the axis of the cylinder.

11. In a grain-separator, the combination of a cylinder having a cellular surface with a feed-trough located adjacent thereto, and adjustable, substantially as described, circumferentially about said cylinder.

12. In a grain-separator, the combination of a cylinder having a cellular surface with a rotary delivery-brush, I, adjustable circumferentially about the said cylinder in the manner and by means substantially as described.

13. In combination with the cylinder having the cellular surface, the rocking frames C, the feed-trough, the delivery-brush, the delivery-screw mounted in said frames, and means, substantially as described, for locking said frames in different positions.

14. In combination with the cellular cylinder and the wheel L''' , applied to its axis, the revolving frames C, the delivery-brush, the feed-screw and the delivery-screw mounted in said frames, and provided with driving-pulleys at their ends, and the driving-chains R S, applied substantially as described.

PIETER VAN GELDER.
